Inventor:

United States Patent Office.

CORNELIUS H. TIEBOUT, OF NEW YORK, N. Y.

Design No. 5,039, dated June 20, 1871.

DESIGN FOR A TWINE-REEL.

The Schedule referred to in these Letters Patent and making part of the same.

To all whom it may concern:

Be it known that I, CORNELIUS H. TIEBOUT, of the city, county, and State of New York, have invented a new and original Design for Twine-Reel; and I do hereby declare the following to be a full, clear, and exact description thereof, which will enable those skilled in the art to make and use the same, reference being had to the accompanying drawing forming part of this specification, in which drawing—

Figure 1 represents a front view of this design.

Figure 2 is an end view of the same.

Similar letters indicate corresponding parts.

This design relates to the peculiar form or shape of the base or bed-plate of a twine-reel, and of the side frames which form the bearings for the gudgeons of the reel, and one of which also is provided with an ornamental chamber inclosing the driving-gear.

In the drawing—

The letter A designates the base or bed-plate, which is composed of an ogee-shaped member, a, a flat member, b, and a convex member, c, and a vertical member, c'.

From this bed-plate rise the side frames B B', which form the bearings for the gudgeons of the reel C, and

which are formed with concave flanges d overlapping the heads of the reel.

The faces of the side frames are ornamented with arabesques e, and they are supported each by two arins, f g, one of which is crescent-shaped, while the other forms an easy curve, as shown in Fig. 2.

From one of the side frames B' rises a pear-shaped cap, D, the small portion of which is concentric with said side frame and ornamented by rings h, while the large portion of said cap is ornamented by arabesques i.

Said cap is intended to receive the gears, by which the motion of the hand-crank E is transmitted to the reel.

What I claim as new, and desire to secure by Letters Patent, is—

1. The design for the bed-plate of a twine-reel, as shown and described.

2. The design for the side frame B, as shown and described.

3. The design for the side frame B' with its cap D, as shown and described.

Witnesses: CORNELIUS H. TIEBOUT.

A. C. RAWLINGS,

E. A. NEWMAN.
